(57) **CLAIM**

The ornamental design for an oscillating turning device for tennis ball launcher, as shown and described.

DESCRIPTION

1. Oscillating turning device for tennis ball launcher
Figure 1.1 shows a front, top, right-side perspective view of the oscillating turning device for tennis ball launcher of the Applicant's design.
Figure 1.2 is a front, bottom, left-side perspective view of FIG.1.1.
Figure 1.3 shows a rear view of FIG.1.1.
Figure 1.4 shows a right view of FIG.1.1.
Figure 1.5 shows a left view of FIG.1.1.
Figure 1.6 shows a front view of FIG.1.1.
Figure 1.7 shows a bottom view of FIG.1.1, wherein the top cover is at a center position with respect to the base part.
Figure 1.8 shows a top view of FIG.1.1.
Figure 1.9 shows a bottom view of FIG.1.1, wherein the top cover is at a right position with respect to the base part.
Figure 1.10 shows a bottom view of FIG.1.1, wherein the top cover is at a left position with respect to the base part.
The broken lines shown in Figs.1.2, 1.3, 1.4, 1.5, 1.6, 1.7, 1.9, and 1.10, represent portions of the oscillating turning device for tennis ball launcher that form no part of the claimed design.
